UNITED STATES PATENT OFFICE.

JANE GRAY STOKES, OF NEW YORK, N. Y.

DESIGN FOR A DOLL.

Application filed August 24, 1922. Serial No. 3,548. Term of patent 7 years.

To all whom it may concern:

Be it known that I, JANE GRAY STOKES, a citizen of the United States, residing in the city of New York, borough of Manhattan, in the county of New York and State of New York, have invented a new, original, and ornamental Design for Dolls, of which the following is a specification, reference being had to the accompanying drawings, forming a part thereof, and of which Figure 1 is a front elevation and Fig. 2 is a rear elevation of a doll showing my new design.

The doll comprises a body, head, legs, and tail made of patent leather suitably stuffed,

and with the seams, as indicated by double parallel lines, all bound with a fabric of a color distinct from and contrasting with the color of the leather. The design is further characterized by a coat of fabric and flanges around the legs of the same material as the coat to give an indication of boots, the color of the coat and boot tops also contrasting with the color of the body and other parts of leather.

I claim:

The ornamental design for a doll, substantially as shown and described.

JANE GRAY STOKES.
